APPARATUS FOR TREATING LIQUID WITH GAS

Filed March 21, 1924

INVENTOR
William E. Greenawalt,

UNITED STATES PATENT OFFICE.

WILLIAM E. GREENAWALT, OF DENVER, COLORADO.

APPARATUS FOR TREATING LIQUID WITH GAS.

Application filed March 21, 1924. Serial No. 700,833.

To all whom it may concern:

Be it known that I, WILLIAM E. GREENAWALT, a citizen of the United States, residing in the city and county of Denver and State of Colorado, have invented certain new and useful Improvements in Apparatus for Treating Liquid with Gas, of which the following is a specification.

The invention has as its object the effective atomization, or fine subdivision, of gas in liquid, to accomplish certain results, as for example, the application of gas to liquid to facilitate desired chemical reactions, and in the flotation treatment of ores, as also in the pneumatic agitation of liquid and ore pulp, and in the application of corrosive gases, such as sulphur dioxide or chlorine, to the treatment of copper, gold, and silver ores.

20 The description of the invention will be more particularly directed to the flotation treatment of ores.

In the flotation treatment of ores excellent results have been obtained by applying air or gas to the ore pulp through porous material in the lower portion of the tank containing the ore pulp. In doing this, certain difficulties have arisen, among which may be mentioned the delicate nature of the porous material if it is made of woven fabric, the clogging of the pores if inorganic porous material is used, and the settling of the sands on the porous material and consequent unequal distribution of the air in, 35 worn or clogged material.

To overcome these difficulties, jets of air have been injected into the liquid, and the impingement of the air against the liquid or against a submerged solid obstacle subdivides the air and gives encouraging results, although these results are far from being satisfactory.

Excellent atomization, or fine subdivision, of gas in liquid is obtainable by introducing gas and liquid into a hollow rotary member and ejecting a mixture of gas and liquid into the surrounding liquid in which the rotary member is submerged, as disclosed in my Patents No. 1,374,500, April 12, 1921, 45 No. 1,350,605, Aug. 24, 1920, and No. 1,374,446, April 12, 1921, but it is not always convenient to operate in that way, and the apparatus, while under excellent control, is somewhat expensive to install. In the

present invention it is desired to get substantially the same control and the same effective atomization of the gas by substituting a hollow stationary gas diffusing member for the rotary member in the patents referred to.

While some machines are more effective in atomizing gas in liquid than others, it is thought that the degree of atomization is largely dependent on the power used. For example, from five to six pounds pressure is required to force air through a porous member to get suitable subdivision for effective flotation. This corresponds to about a static head of twelve feet of liquid, such as water or ore pulp, if air is introduced into it through an unrestricted inlet. If a satisfactory atomization of the gas is obtainable without the use of porous membranes or rotary members it is evident that both the construction and operation of the apparatus will be simplified.

Primarily, the efficiency of any apparatus for treating liquid with gas is more or less proportional to the degree of subdivision of the gas, and merely introducing a gas into the liquid without effective subdivision would be of no advantage, no matter how simple the apparatus might be.

I have found that excellent atomization or subdivision of gas in liquid is obtainable by a combination of the principle of the air lift and a substantially horizontal gas diffusing upper portion with radially disposed outlets, submerged in the liquid of the tank containing the gas diffusing member. This general arrangement gives satisfactory atomization and diffusion without clogging and without resorting to rotary mechanism. Moreover, the apparatus can be constructed in large units, and this is highly desirable, since it is cheaper and better to have a few large units for a desired capacity than a multiplicity of small units.

The invention will now be described in detail, reference being made to the accompanying drawings, in which Fig. 1 represents a vertical cross section of the apparatus; Fig. 2 the corresponding longitudinal section; Fig. 3 a horizontal section 105 through one compartment of the apparatus on the line 3-3 of Fig. 1; Fig. 4 a vertical section of the gas atomizer or gas

diffusing member on an enlarged scale; and Fig. 5 a horizontal section on the line 5—5 of Fig. 4.

Referring to the drawings, 1 is a tank 5 adapted to contain the liquid to be treated, and which may be divided into compartments *a*, *b*, and *c*, by the partitions 4. Each compartment may be divided into an agitating chamber 2 and a settling chamber 3, 10 when used for the flotation treatment of ores. Within the agitating chamber is an atomizer or gas diffusing member 5, taken as a whole, through which gas and liquid are distilled into the surrounding liquid in the tank. The atomizer or gas diffusing member 5, consists of a lower vertical tube 6 communicating with a hollow upper horizontal diffusing member 8 provided with suitable discharge passages. A gas inlet pipe 7 15 communicates with the lower portion of the tube 6 and with the blower 20, which furnishes compressed air or other gas. The upper portion 8 of the atomizer 5 has radial or outwardly directed discharge passages 9 communicating with the vertical tube 6 and with the liquid in the tank. The upper portion of the atomizer is preferably provided with a dome or space 10, which serves as a mixing chamber for the gas and liquid before 20 the gas and liquid are ejected from the atomizer into the surrounding liquid in the tank. The abrupt changing of the flow of gas and liquid from the vertical to the horizontal in the interior of the atomizer causes effective 25 mixing, but the mixing is improved by the dome 10 in the upper portion of the atomizer. The interior of the agitating chamber 2 is preferably arranged so that issuing streams of gas and liquid from oppositely positioned discharge passages will be diffused. This is done by means of the deflecting 30 projections 11 in the agitating chamber. The various compartments communicate with one another through openings 13 and 14 in the partitions 4 and openings, or communicating passages, are preferably provided both in the upper and lower portion of the tank. The lower openings 13 are adapted to let heavy particles, in suspension 35 in the liquid, pass from one compartment to the next, while the upper openings 14 provide for the passage of the finer particles, or slimes. The material to be treated is fed into the inlet pipe 15 and the residue flows 40 out through the outlet pipe 17. The outlet pipe 17 is preferably provided with a weir overflow 18 to take most of the liquid and fine particles and provides for a uniform liquid level in the various compartments of the tank, while the under flow 19 may take the heavier particles which cannot easily be 45 lifted to the overflow.

The compressed air or gas is provided by the blower 20 and is supplied to the atomizers through the pipe main 21 and the

branch pipes 22 leading to the various compartments, and the amount of flow may be independently regulated to the various compartments by the valves 23 in the branch lines 22.

The partitions forming the discharge passages in the upper portion 8 of the atomizer are preferably curved or arranged at an angle from the direct straight radial line. This gives a swirling or rotary movement to 70 the streams of issuing gas and liquid so that they commingle and give a fairly uniform distribution of the gas in fine particles in the ascending column of liquid in the agitating compartment. The mixing is further improved by the projecting members 11 at 75 the sides of the agitating chamber. Much the same results are obtained in this way, with a stationary atomizer or gas diffusing member, as are obtained with the rotary atomizer or gas diffusing member in the 80 patents referred to. The tube 6 is preferably enlarged at its lower portion so as not to restrict the area for entering liquid due 85 to the insertion of the gas pipe 7.

Assuming the tank to be filled with ore pulp of the proper consistency and mixed with a suitable frothing agent, the operation of the apparatus as applied to flotation may be briefly described as follows: The blower is started and the amount of air delivered to the various compartments is regulated by the valves 23 to give the effect desired for each compartment, as can at once be observed by the froth produced on the 90 surface of the liquid. The air, introduced into the tube 6 of the atomizer, acts as an energetic air lift for both liquid and suspended particles. When the ascending stream of air and pulp or liquid hits the upper portion 8 of the atomizer and the direction of the stream is abruptly changed, an intense mixing or atomizing action takes place and the gas and liquid is ejected from the interior of the atomizer into the surrounding liquid in the tank with the gas in 95 finely divided bubbles. This action is intensified by the dome or mixing space 10, since the up-rushing current of gas and liquid meets the down-rushing current in the mixing space, and an intense mixing action takes place. The energy of the compressed air, in the ascending current of air and liquid, is spent in thoroughly mixing, 100 or atomizing, the gas in the liquid, while at the same time the velocity of the ascending stream of gas and liquid is reduced to the desired amount to avoid excessive agitation, or surging of the liquid at the surface, which would interfere with effective flotation.

The apparatus finds its best application in large units, as will be evident from the following considerations: A low depth of liquid, and consequently a low pressure of 130

air, does not provide conditions for effective atomization of the air. Suppose, however, that the tank is twelve feet deep, which implies an air pressure of about six pounds per square inch to deliver the air into the vertical tube 6, which is about the pressure required to force air through porous membranes in the bottom of tanks for effective flotation. This air will ascend with liquid from the tank at a considerable velocity and the current of air and liquid will contain sufficient energy for the effective atomization of the air in the upper portion of the atomizer. With such a depth of liquid, large unit installations are made possible, which is a thing to be desired in flotation, as in other metallurgical processes. Assuming an atomizer four feet in diameter and an agitating chamber six feet square with a corresponding settling chamber, it will be seen that the capacity of each compartment is approximately twenty tons of water, and if the ratio of pulverized ore to water desired for effective flotation is 1:4, each compartment will hold about five tons of ore under treatment, and if a unit tank, or installation, consists of ten compartments, fifty tons of ore would be under treatment at one time in each unit. If the ore is given two hours' treatment the daily capacity would be 600 tons, and if given one hour treatment the daily capacity would 1200 tons of ore.

Assuming a convenient compartment unit, the number of compartments will be determined by the daily capacity desired, and the number may range from one to ten or fifteen or even more, depending on the results desired.

The depth of submergence of the atomizer will be determined by the results desired. Ordinarily the best results for flotation will be obtained, say in a tank twelve feet deep, by having a long vertical tube or air lift so as to get as much momentum as possible in the upward current of gas and liquid, and then eject the mixture of air and liquid from two to three feet below the surface of the liquid. This will give a positive circulation of the ore pulp and there will be no objectionable agitation or surging of the surface of the liquid. The size of the ore particles which can be effectively circulated to prevent clogging will depend largely on the amount of air or gas circulated through the atomizer.

The apparatus can be effectively used in the treatment of ores with corrosive gases, such as chlorine, sulphur dioxide, or ammonia. If iron is attacked by the corrosive gas or solution the atomizer may be made of antimonial lead, ferro silicon, or any other noncorrosive substance.

The best number of discharge passages in the diffusing member 8 is determined by experiment and may vary within wide limits.

The mixture of gas and liquid is ejected in sheet-like form from the diffusing member, while the partitions forming the discharge passages give a whirling motion to the surrounding liquid in the tank to thoroughly diffuse the gas in the tank liquid. 70

I claim:

1. In apparatus for treating liquid with gas, a tank adapted to contain liquid, a hollow stationary gas diffusing member within the tank submerged in the liquid comprising a vertical tube with its lower end in communication with the tank and its upper end in communication with outwardly directed discharge passages adapted to discharge gas 80 and liquid from the interior of the hollow gas diffusing member in different directions into the surrounding liquid in the tank, and means for supplying gas to the interior of said vertical tube. 85

2. In apparatus for treating liquid with gas, a tank adapted to contain liquid, a stationary hollow gas diffusing member having curved, substantially radially disposed discharge passages within the tank submerged 90 in the liquid and adapted to eject a mixture of gas and liquid from its interior into the surrounding liquid in the tank, means to deliver gas and liquid into said diffusing member, said radial discharge passages being 95 curved so that streams of gas and liquid issuing therefrom will impart a swirling motion to the surrounding liquid in the tank, and means for supplying gas to the interior of the hollow gas diffusing member. 100

3. In apparatus for treating liquid with gas, a tank adapted to contain liquid, a hollow stationary member within the tank submerged in the liquid comprising a vertical tube open at its lower end and communicating with outwardly directed discharge passages at its upper end, means for introducing gas and liquid through the tube into the interior of the hollow gas diffusing member, and means adapted for mixing the gas and liquid within the gas diffusing member. 105 110

4. In apparatus for treating liquid with gas, a tank adapted to contain liquid, a hollow stationary gas diffusing member comprising a vertical tube communicating with outwardly disposed discharge passages at its upper end and with the tank at its lower end and a dome or chamber communicating with both the vertical tube and with the discharge passages, and means for delivering gas to the interior of the vertical tube. 115 120

5. In apparatus for treating liquid with gas, a tank adapted to contain liquid, a hollow stationary gas diffusing member submerged in the liquid comprising a vertical tube communicating with the tank at its lower end and with a submerged fluid receiving member at its upper end, said fluid receiving member being adapted to receive 125 130

gas and liquid from the vertical tube and diffuse the gas and liquid in different directions into the surrounding liquid in the tank, and means for delivering gas into the interior of the vertical tube.

6. In apparatus for treating liquid with gas, a tank adapted to contain liquid divided into an agitating chamber and a settling chamber, the bottom of said agitating chamber being in communication with the settling chamber, a hollow stationary gas diffusing member submerged in the liquid comprising a vertical tube communicating with the settling chamber at its lower end and with a submerged fluid receiving member at its upper end, said fluid receiving member being located within the agitating chamber and adapted to receive gas and liquid from the vertical tube and diffuse the gas and liquid in different directions into the surrounding liquid in the agitating chamber, and means for delivering gas to the interior of the vertical tube.

7. In apparatus for treating liquid with gas, a tank adapted to contain liquid, a stationary hollow gas diffusing member comprising means for receiving separate streams of gas and liquid in the lower portion of the tank and discharge outlets for ejecting a mixture of gas and liquid into the surrounding liquid in the upper portion of the tank, and horizontal stationary deflecting members arranged in proximity to the discharge outlets adapted to deflect opposite streams of issuing gas and liquid toward one another so that they will mix and be diffused in the liquid in the tank.

8. In apparatus for treating liquid with gas, a tank adapted to contain liquid, a hollow stationary gas diffusing member submerged in the liquid comprising a vertical tube open at its lower end and communicating with a mixing chamber at its upper end said mixing chamber communicating with outwardly directed discharge passages,

and means for delivering gas to the interior of the vertical tube.

9. In apparatus for treating liquid with gas, a tank adapted to contain liquid, a hollow stationary gas diffusing member within the tank submerged in the liquid comprising a mixing chamber a vertical tube communicating with the lower portion of the tank and with the mixing chamber and oppositely positioned discharge passages communicating with the mixing chamber and with the upper portion of the tank, and means for delivering gas to the interior of the vertical tube.

10. In apparatus for treating liquid with gas a tank adapted to contain liquid, a hollow stationary gas diffusing member within the tank submerged in the liquid comprising a vertical tube with its lower end in communication with the tank and its upper end in communication with outwardly directed discharge passages adapted to discharge gas and liquid in sheet-like form into the surrounding liquid in the tank, and means for supplying gas to the interior of said vertical tube.

11. In apparatus for treating liquid with gas, a tank adapted to contain liquid divided into an agitating chamber and a settling chamber the bottom of said agitating chamber being in communication with the settling chamber, a hollow stationary gas diffusing member within the tank comprising a vertical tube communicating with the settling chamber at its lower end and with a fluid receiving member at its upper end, said fluid receiving member being located within the agitating chamber and adapted to receive gas and liquid from the vertical tube and diffuse the gas and liquid in different directions in the agitating chamber, and means for delivering gas into the interior of the vertical tube.

WILLIAM E. GREENAWALT.
